UNITED STATES PATENT OFFICE

134,593

DESIGN FOR A HAIR ROLL FOUNDATION

Ross McCroy McFadden, Los Angeles, and Earl C. Thompson, North Hollywood, Calif.; said Thompson assignor to said McFadden

Application June 15, 1942, Serial No. 107,202

Term of patent 14 years

To all whom it may concern:

Be it known that we, Ross M. McFadden and Earl C. Thompson, citizens of the United States, residing at Los Angeles and North Hollywood, respectively, in the county of Los Angeles and State of California, have invented a new, original, and ornamental Design for a Hair Roll Foundation, of which the following is a specification, reference being had to the accompanying drawing, forming part thereof:

The figure is a plan view of a hair roll foundation showing our new design.

We claim:

The ornamental design for a hair roll foundation, as shown.

ROSS McCROY McFADDEN.
EARL C. THOMPSON.
